UNITED STATES PATENT OFFICE.

HERBERT J. GROSVENOR, OF FORT WAYNE, INDIANA, ASSIGNOR TO S. F. BOWSER & COMPANY, INCORPORATED, OF FORT WAYNE, INDIANA, A CORPORATION OF INDIANA.

DESIGN FOR A SELF-MEASURING PUMP.

41,839.

Specification for Design.

Patented Oct. 10, 1911.

Application filed July 26, 1911. Serial No. 640,704. Term of patent 14 years.

To all whom it may concern:

Be it known that I, HERBERT J. GROSVENOR, a citizen of the United States, residing at Fort Wayne, in the county of Allen and State of Indiana, have invented a new, original, and ornamental Design for a Self-Measuring Pump, of which the following is a specification, reference being had to the accompanying drawing, forming part thereof.

The figure is a view in elevation of a self-measuring pump, showing my new design.

I claim:

The ornamental design for a self-measuring pump, as shown.

HERBERT J. GROSVENOR.

In the presence of—

C. M. SMITH,

J. W. BURROWS.
